UNITED STATES PATENT OFFICE.

ALBERT T. FAY, OF MINNEAPOLIS, MINNESOTA, ASSIGNOR TO ANTON HUHN, OF MINNEAPOLIS, MINNESOTA.

WHEAT-HEATER.

1,283,486.

Specification of Letters Patent.

Patented Nov. 5, 1918.

Application filed March 10, 1917. Serial No. 153,996.

To all whom it may concern:

Be it known that I, ALBERT T. FAY, a citizen of the United States, residing at Minneapolis, in the county of Hennepin and State 5 of Minnesota, have invented certain new and useful Improvements in Wheat-Heaters, of which the following is a specification.

My invention relates to wheat heaters, and has for its object to provide a wheat heater 10 of the type wherein a substantially horizontal rotating cylinder is employed, with means for properly adjusting, in elevated position, the grain receiving end of the cylinder so that the entire cylinder will have a 15 required amount of slope from the grain receiving end to the discharge end; and, further, to provide means for properly receiving and resisting the end thrust of such cylinder when the same is so forwardly 20 sloped, together with means for driving the cylinder.

The full objects and advantages of my invention will appear in connection with the detailed description thereof, and are particularly pointed out in the claims.

In the drawings, illustrating the application of my invention in one form,—

Figure 1 is a side elevational view of a wheat heater embodying my improvements. 30 Fig. 2 is a front elevation view of the same, with some parts broken away. Fig. 3 is an enlarged sectional detail view of the driving and end thrust receiving mechanism. Figs. 4, 5, and 6 are sectional detail views showing means for adjusting and stabilizing the adjusting or grain receiving end of the wheat heater.

As illustrated, the end supports 10 and 11 have journaled therein rollers 12 and 13 40 upon which rest rings 14 and 15 of a cylinder 16 rotatably supported between said end supports on said rings. The end supports are held in properly relative position by connecting rods 17. Each of the end supports 45 10 and 11 is provided with a pair of feet 18. If the wheat heater sets upon these four feet, it will be held substantially horizontal. It is desirable, however, to adjust the grain receiving end of the wheat heater somewhat 50 higher than the discharge end, and it is frequently desirable to change this adjustment for operating upon different grades of grain. To provide means for holding the heater in the proper position of adjustment, I arrange 55 a movable base 19 having a horizontal top

20 in combination with a second base member 21 having a top 22 angularly disposed in respect to top 20 so as to be in parallel and engaging rotation with the face 23 of foot 18. In practice, a series of secondary supports 21 are provided of varying heights so that different degrees of elevation of the end support 10 may thereby be effected, resulting in different degrees of forward slope to the cylinder 16. The top 20 of base 19 is 60 provided with an elongated slot 24 through which extends a bolt 25 which enters or is secured in the floor or other pedestal support of the machine and which bolt extends through a slot 26 in top 22 of base member 70 21 and through the wall 23 of foot 18 having threads on the end thereof and nut 27. Within the space 28 below the top 22 of base member 21, and resting upon the top 20 of base member 19 is a support or socket 75 piece 29 which provides a fulcrum for the lower end of a bolt 30 threaded through the wall 23 of foot 18. After the second base member 21 has been put in position and the nut 27 and bolt 30 have been tightened to 80 the desired extent, the parts will be held rigidly together as a unit and the adjustment of the receiving end of the wheat heater will be properly effected. In order to change the base member 21 for a higher 85 or lower member as desired, the nut 27 is withdrawn from bolt 25, and bolt 25 removed. The bolt 30 is then screwed up so as to lift the foot 18 from off the base member 21. This is then pushed over, the bolt 90 30 traveling along slot 26 until the inner wall of member 21 contacts with the socket piece 29 and a new member of the desired height, having therein a suitable socket piece, is inserted in the space from which the 95 member 21 has been removed. The bolt 30 is then unscrewed permitting the foot 18 to rest upon the newly inserted base member. The old base member 21 and the old socket block 29 may then be removed and the new 100 base member with its socket member may be driven into position beneath the foot 18 when the bolts 25 and 30 may be restored and the end support 10 thus screwed in proper adjusted elevation.

The ring 15 is a part of a casting encircling cylinder 16 which has secured thereon an annular spur gear 31 and a forwardly extending bearing piece 32, which bearing piece has a face 33 engaging against 110

beveled rollers 34 journaled upon studs 35, fast on a portion of the end casting 11. One of the rollers 13, as shown in Figs. 1 and 3, is fast on a shaft 36 having on one end a 5 spur pinion 37 meshing with spur gear 31 and on the other end a pulley 38 by which shaft 36 and pinion 37 are driven, thereby rotating the cylinder 16. It will be noted that the cylinder 16 rests by gravity only 10 upon rollers 12 and 13. It follows that when the cylinder is in the forwardly inclined position shown in Fig. 1, it will tend to move forward. This brings the face 33 in contact with the angularly positioned 15 rollers 34, thus resisting the end thrust tendency of the cylinder and holding it in a fixed position longitudinally while permitting the utmost freedom of revolution.

I claim:

20 1. A wheat heater comprising a rotary cylinder, means for supporting said cylinder in an inclined position including a foot member at one end of said cylinder having an inclined bottom, a primary base member 25 adapted to rest upon the floor underneath and spaced from said foot member, and a secondary base member adapted to be inserted between said primary base member and said foot member, said secondary base member having an inclined top to coöperate with the inclined bottom of said foot member.

2. A wheat heater comprising a rotary cylinder, means for supporting said cylinder in an inclined position including a foot 35 member at one end of said cylinder having an inclined bottom, a primary base member adapted to rest upon the floor underneath and spaced from said foot member, a secondary base member adapted to be inserted 40 between said primary base member and said foot member, said secondary base member having an inclined top to coöperate with an inclined bottom of said foot member, means for lifting said foot member to permit insertion of different sized secondary base members, and means for holding said primary 45 and secondary base members in position beneath said foot member.

3. A wheat heater comprising a rotary

cylinder, means for supporting said cylinder 50 in an inclined position including a foot member at each end, the foot member which is at one end being provided with a screw threaded hole in its bottom, a screw threaded bolt adapted to be screwed into said 55 screw threaded hole from above, a primary base member adapted to rest upon the floor underneath and spaced from said foot member, a secondary base member adapted to be inserted between said primary base member 60 and said foot member, said secondary base member having an elongated slot in its top, and a relatively small support adapted to rest upon the primary base member in position to be engaged by said screw threaded 65 bolt for lifting said foot member to permit insertion of different sized secondary base members.

4. A wheat heater comprising a rotary cylinder, means for supporting said cylinder in an inclined position including a foot member which is at one end being provided with a screw threaded hole in its bottom, a screw threaded bolt adapted to be screwed into said screw 70 threaded hole from above, a primary base member adapted to rest upon the floor underneath and spaced from said foot member, a secondary base member adapted to be inserted between said primary base member 75 and said foot member, said secondary base member having an elongated slot in its top, a relative small support adapted to rest upon the primary base member in position to be engaged by said screw threaded bolt 80 for lifting said foot member to permit insertion of different sized secondary base members, said foot member being provided with a second hole in its bottom, a bolt anchored beneath said primary base member 85 and having a screw threaded upper end adapted to extend loosely through said second hole, and a nut adapted to be screwed upon said screw threaded end to hold said primary and secondary base members in 90 position beneath said foot member.

In testimony whereof I affix my signature.

ALBERT T. FAY.
